UNITED STATES PATENT OFFICE.

MARTIN V. B. ETHRIDGE, OF BROOKLYN, NEW YORK, ASSIGNOR TO AUGUSTE T. RIEDINGER, OF NEW YORK, N. Y.

FLUID-OPERATED MOTOR.

1,163,330.

Specification of Letters Patent.

Patented Dec. 7, 1915.

Application filed March 31, 1914. Serial No. 828,439.

To all whom it may concern:

Be it known that I, MARTIN VAN BUREN ETHRIDGE, a citizen of the United States, and a resident of Brooklyn, in the county 5 of Kings and State of New York, have invented certain new and useful Improvements in Fluid-Operated Motors, of which the following is a specification.

My invention relates to new and useful 10 improvements in fluid operated motors, the same being designed to be operated by means of a fluid under pressure, such as air, gas, steam, and similar fluids, and the object thereof is to provide an improved fluid operated motor of the type or class in which a series of movable pistons are acted upon by a body of fluid confined between a fixed 15 abutment and one of said pistons, to thereby impart rotary motion to a driving shaft.

With the above and other objects of invention in view, my invention consists in the improved fluid operated motor illustrated in the accompanying drawings, and hereinafter described and claimed, and in 20 such variations and modifications thereof as will be obvious to those skilled in the art to which my invention relates.

Referring now to the drawings accompanying and forming part of this application, and in which the preferred embodiment of my invention is illustrated—Figure 1 is a view illustrating my improved fluid operated motor in perspective; Fig. 2 is a view showing a section of the same taken upon a 25 central plane extending longitudinally of the motor axis; Fig. 3 is a view showing one of the halves of the casing of my improved motor, together with the various elements contained within said casing, looking toward the right, Fig. 2; Fig. 4 is a similar view, showing the other of the two parts of the casing of my motor, looking toward the left, Fig. 2; Fig. 5 is a view showing the rotary piston carrying member of my improved 30 motor in perspective; Fig. 6 is a similar view showing a stationary cam member of my improved motor; Fig. 6^a is a view showing a section of the same upon a plane indicated by the line 6—6, Fig. 6; Fig. 7 is a view in perspective illustrating the interior construction of the right-hand portion of the casing of my motor; and Figs. 8 to 10 are fragmentary views illustrating certain de-

tails of construction of my improved fluid operated motor.

55

My improved motor includes a suitable casing made up of two members, 11, 12, the same being provided with flanges at their inner ends, as illustrated, whereby they may be secured together to form a unitary motor 60 casing. This motor casing is hollow, and a fluid under pressure may be supplied thereto through a suitable pipe connected with an opening shown at 13 to thereby charge the interior of the casing with fluid 65 under pressure.

Referring now to Fig. 7, the interior of the portion 11 of the motor casing is provided with a circumferentially extending cam surface beginning at the point indicated by the reference character 14 and extending in a plane perpendicularly to the axis of the motor throughout about 90 degrees, or to the point 15, after which it assumes the spiral form and terminates at the 70 point 16 in an abutment 26 extending parallel with the shaft of the motor. This portion 11 of the casing is also provided with a circular seat shown at 17, and the reference numeral 18 indicates a stationary cam member 80 formed separate from the casing, and the exterior of which is cylindrical, as shown.

This cam member is provided with a projecting sleeve 19, through which the driven shaft 20 of the motor extends, as best shown 85 in Fig. 2, and the end of this sleeve is fixed in a flange 21 secured to the inner surface of the second part 12 of the motor casing, as clearly shown in Fig. 2.

The stationary cam member above referred to is provided with a cam surface upon its periphery, which cam surface is indicated by the reference numeral 22, and the form of which corresponds with the form of the cam surface hereinbefore referred to, as provided within the portion 11 of the casing. The exterior diameter of this stationary cam member is less than the diameter of the seat 17, so as to provide an annular space between the periphery of the 95 cam member and the circular seat 17 of portion 11 of the casing, within which annular space a piston carrying member, to be hereinafter more specifically referred to, operates, and the cam member is secured in position within the motor casing in such a man-

2
ner that its cam surface 22 corresponds with the cam surface in the portion 11 above referred to. Said cam member is provided with an annular wall 23, which wall in connection with the inner annular wall of the casing member 11, indicated by the reference numeral 241, Fig. 7, provides an annular circumferentially extending channel or raceway, the bottom wall of which is 10 made up of the two cam surfaces upon the casing member 11 and stationary cam member hereinbefore referred to.

The stationary cam member is provided with a recess, as shown at 24, and 25 is a 15 port leading from this recess and into the annular raceway above referred to, which port is located adjacent the abutment hereinbefore referred to at the ends of the cams,—the location of these abutments being 20 at or about the point 26, Fig. 3.

The reference numeral 27 designates a rotary piston carrying member secured to the shaft 20, and through which the shaft is driven. The periphery of this piston carrying member extends parallel with the shaft 25 of the motor and fits in between the annular seat 17 upon the casing member 11 and the periphery of the stationary cam member 18, as best shown in Figs. 2 and 3 of the drawing; and the periphery of said member is 30 provided with a series of slots 28. This piston member serves as a support for a plurality of driving pistons upon which the fluid under pressure acts, and through which motion is transmitted to the driving shaft 35 20. These pistons are illustrated as six in number, and they are of such dimensions as to move along the raceway hereinbefore referred to, and as will be understood from Figs. 2 and 3. These pistons may be of any 40 form, but are shown as substantially rectangular. They are formed from thin tubing, as illustrated in the drawing, and opposite peripheral walls of each of said pistons 45 enter into and slide parallel with the shaft of the motor in the slots 28 of the piston carrying member. When the motor is in operation, these pistons travel within the channel or raceway as above explained, during which movement they are also moved toward the left, Fig. 2, by the cam surface 50 formed by the bottom wall of said raceway until they are carried past the highest point of the cams, that is, past the abutment 26, whereupon they are moved to the right and 55 into a position in front of the abutment 26 by a piston operating mechanism to be hereinafter described. The fluid under pressure passes from the space 24 through the port 60 25, and acts within the chamber formed between the abutments 26, the side and bottom walls of the channel or raceway above referred to and the pistons, this action taking place as each successive piston passes the abutment 26, as will be understood. It will

be appreciated, however, that because of the fact that the pistons are tubular with thin walls, they may be moved in a direction parallel with their axis, or to the left (Fig. 2) with minimum of effort against whatever 70 pressure may exist within the motor casing; whereas the pressure which moves each piston away from the abutment 26 is the full pressure within the motor casing acting upon the entire area of the piston within the annular raceway. 75

The pistons above referred to are designated by the reference numeral 29, and each of them is provided with a crossbar 30. The piston carrying member 27 is provided with a series of guide rollers 31, 32, secured in suitable brackets upon one face thereof, as shown on Fig. 2, and 33 designates flexible piston operating members extending about said guides, and the inner ends of which 80 members are connected with the crossbars 30, through suitable swivel connections to avoid binding of the parts. The other ends of the flexible members 33 are connected with the springs 34, which springs in turn are 85 connected to one of a series of pins carried by a collar 35, secured to the shaft 20. The number of springs and flexible connections correspond with the number of pistons as will be understood, and it will also be obvious 90 that the tendency of the springs 34 is to draw the pistons 29 toward the right, Fig. 2, and keep the ends of said pistons in contact with the cam surface formed by the bottom wall of the channel or raceway above 95 referred to.

The reference numeral 36 designates a rotary spider supported upon and free to rotate about the sleeve 19 of the stationary cam member, and which spider in connection with the piston carrying member 27 forms a support for the pistons 29, the spider being provided for the purpose of guiding the pistons as they are moved parallel with the axis of the motor, as hereinbefore explained, while the power due to the action of the fluid under pressure upon said pistons is transmitted to the shaft through the piston carrying member because of the permanent engagement of the pistons therewith. This spider is located within the portion 12 of the motor casing, as will be understood from Fig. 4, and the same is provided with a series of pairs of arms 37, which arms are substantially parallel, and between which the pistons 29 are moved toward the left by the cam surface in the raceway. One arm of each of the pairs of arms is provided with ribs 38, the purpose of which is to keep the adjacent surface of the piston away from the arm upon which said ribs are located, in order to reduce the force necessary to move the pistons into the several pockets formed by the parallel pairs of arms 37. This spider is also provided with a series of lugs 39, each 110 120 125 130

of which carries a guide rod 40, which rod extends through guides 41 one upon the inner surface of each of the pistons 29, in order to more effectively guide the pistons 5 in their movements.

The stationary cam member 18 is provided with a finger 42, located adjacent the port 25, the purpose of which is to delay slightly the movement of the successive pistons 29 into the annular raceway. This is accomplished by providing a stop 43 upon each of the flexible members 33, the arrangement and location of the stop and finger being such that the stop engages a free end 10 of the finger as the pistons pass beyond the highest point 16, of the cam, whereby the pistons are held against movement by the spring 34 for a short time, and until the stop moves away from the free end of the 15 finger, whereupon the flexible member is freed so that the piston with which it is connected may be moved by spring 34 connected with it.

Any suitable mechanism may be provided 25 for the purpose of regulating the speed of my improved motor. I have, however, illustrated a form of governor comprising an eccentric 44, secured to and rotating with the shaft 20, and which eccentric operates a 30 piston 45 located within a cylinder 46, supported in any suitable way, but shown as secured to the motor casing. Leading from this cylinder is a pipe 47 having a valve 48.

In view of the premises, it will be seen 35 that when the valve 48 is in such a position to open a free passage through the pipe 47, a minimum of resistance will be offered to the movement of the piston 45. If, however, the valve 48 be operated to partially 40 close the opening in the pipe 47, the flow of air through the pipe will be restricted, and a load imposed upon the piston 45 which will cause the motor to operate more slowly.

I contemplate using my improved fluid 45 operated motor for operating automobiles and in similar services, in which case the valve 48 will be operated by hand in order to thereby control the speed of the vehicle. Said valve may, however, be operated and is 50 preferably operated when the engine is used as a stationary engine for power purposes by means of any suitable centrifugal governor, as will be understood by those skilled in the art.

55 In view of the premises, it will be understood that each of the pistons 29, after passing the abutment 26, will be acted upon by the fluid under pressure within the annular channel or raceway, which fluid has entered said raceway through the port 25, as above explained. The piston then moves forward through the flat portion of the cam surface which forms the bottom wall of the raceway, or, as hereinbefore explained, 60 through about 90 degrees. The piston then

begins to ride up the inclined portion of said cam surface and continues to do so until it reaches the highest part 16 thereof, as hereinbefore explained, after which it is moved into a position in front of the abutment 26 by the spring 34. This movement of the pistons in a direction parallel to their axes and parallel to the axis of the motor is not opposed by the pressure of the fluid within the motor casing, for the reason that 75 the walls of the pistons are as thin as practicable, as hereinbefore explained.

Having thus described and explained my invention, I claim and desire to secure by Letters Patent:—

1. In a fluid operated motor, a casing comprising two casing members secured together and one of which is provided with an inner annular wall and with a circumferentially extending cam surface terminating in an abutment; a cam member located within and spaced apart from said casing and having an annular wall, and a cam surface corresponding in form with said first mentioned cam surface, the inner annular 90 wall of said first mentioned casing member and the annular wall of said cam member being concentric and forming the sides of an annular channel, and the two cam surfaces aforesaid together forming the bottom wall 95 of said channel; a shaft supported in bearings in said casing; a rotary annular piston carrying member carried by said shaft and operating in the space between said cam member and said casing; a plurality of pistons carried by and movable relative to said piston carrying member and adapted to move along said channel; means for moving each of said pistons into said channel after it has moved past said abutment; and a 100 port adjacent said abutment and through which fluid may flow into said channel.

2. In a fluid operated motor, a casing comprising two casing members secured together and one of which is provided with an inner annular wall, and with a circumferentially extending cam surface terminating in an abutment; a cam member located within and spaced apart from said casing 110 and having an annular wall, and a cam surface corresponding in form with said first mentioned cam surface, the inner annular wall of said first mentioned casing member and the annular wall of said cam member being concentric and forming the sides of 115 an annular channel, and the two cam surfaces aforesaid together forming the bottom wall of said channel; a shaft supported in bearings in said casing; a rotary annular piston carrying member carried by said shaft and operating in the space between 120 said cam member and said casing; a plurality of pistons movable in slots provided in said piston carrying member, and adapted to move along said channel and to move 125 through about 90 degrees. The piston then

also in a direction parallel with the axis of the motor; means for moving each of said pistons into said channel after it has moved past said abutment; a rotary guiding member located within said casing and adapted to guide said pistons in their movements parallel with said shaft; and a port adjacent said abutment and through which fluid may flow from the interior of said casing 10 into said channel.

3. In a fluid operated motor, a casing comprising two casing members secured together and one of which is provided with an inner annular wall, and with a circumferentially extending cam surface terminating in an abutment; a cam member located within and spaced apart from said casing and having an annular wall, and a cam surface corresponding in form with said first 15 mentioned cam surface, the inner annular wall of said first mentioned casing member and the annular wall of said cam member being concentric and forming the sides of an annular channel, and the two cam surfaces aforesaid together forming the bottom wall of said channel; a shaft supported in bearings in said casing; a rotary annular piston 20 carrying member carried by said shaft and operating in the space between said cam member and said casing; a plurality of pistons carried by and movable relative to said piston carrying member and adapted to 25 move along said channel; operating means including a spring adapted to move each 30 piston into said channel after it has moved past said abutment; and a port adjacent said abutment and through which fluid may flow into said channel.

4. In a fluid operated motor, a casing 40 comprising two casing members secured together and one of which is provided with an inner annular wall, and with a circumferentially extending cam surface terminating in an abutment; a cam member located 45 within and spaced apart from said casing and having an annular wall, and a cam surface corresponding in form with said first mentioned cam surface, the inner annular wall of said first mentioned casing member and the annular wall of said cam member being concentric and forming the sides of an annular channel, and the two cam surfaces aforesaid together forming the bottom wall of said channel; a shaft supported 50 in bearings in said casing; a rotary annular piston carrying member carried by said shaft and operating in the space between said cam member and said casing; a plurality of pistons each tubular in form and 55 movable in slots provided in said piston carrying member and adopted to move along said channel; a flexible member associated with each of said pistons, one end thereof being connected with its piston, a spring 60 associated with each flexible member and to

which the free end of the corresponding flexible member is connected and the other ends of which springs are connected with said shaft; guides carried by said piston carrying member and about which said flexible members extend; and a port adjacent said abutment and through which fluid may flow into said channel.

5. In a fluid operated motor, a casing comprising two casing members secured together and one of which is provided with an inner annular wall, and with a circumferentially extending cam surface terminating in an abutment; a cam member located within and spaced apart from said casing and having an annular wall, and a cam surface corresponding in form with said first mentioned cam surface, the inner annular wall of said first mentioned casing member and the annular wall of said cam member being concentric and forming the sides of an annular channel, and the two cam surfaces aforesaid together forming the bottom wall of said channel; a shaft supported in bearings in said casing; a rotary annular piston 90 carrying member carried by said shaft and operating in the space between said cam member and said casing; a plurality of pistons carried by and movable relative to said piston carrying member and adapted to 95 move along said channel; means for moving each of said pistons into said channel after it has moved past said abutment; means for preventing said last mentioned movement until the pistons have moved a short distance beyond said abutment; and a port adjacent said abutment and through which fluid may flow from the interior of said casing into said channel.

6. In a fluid operated motor, a casing comprising two casing members secured together and one of which is provided with an inner annular wall, and with a circumferentially extending cam surface terminating in an abutment; a cam member located within and spaced apart from said casing and supported from the other member thereof, and which cam member is provided with an annular wall, and with a cam surface corresponding in form with said first mentioned cam surface, the inner annular wall of said first mentioned casing member and the annular wall of said cam member being concentric and forming the sides of an annular channel, and the two cam surfaces aforesaid together forming the bottom wall of said channel; a shaft supported in bearings in said casing; a rotary annular piston carrying member carried by said shaft and operating in the space between said cam member and said casing; a plurality of pistons carried by and movable relative to said piston carrying member and adapted to move along said channel; means for moving each of said pistons into said channel after 120

it has moved past said abutment; and a port adjacent said abutment and through which fluid may flow into said channel.

7. In a fluid operated motor, a casing comprising two casing members secured together and one of which is provided with an inner annular wall, and with a circumferentially extending cam surface terminating in an abutment; a cam member located within and spaced apart from said casing and supported from the other member thereof, and which cam member is provided with an annular wall, and with a cam surface corresponding in form with said first mentioned cam surface, the inner annular wall of said first mentioned casing member and the annular wall of said cam member being concentric and forming the sides of an annular channel, and the two cam surfaces aforesaid together forming the bottom wall of said channel; a shaft supported in bearings in said casing; a rotary annular piston carrying member carried by said shaft and op-

erating in the space between said cam member and said casing; a plurality of pistons 25 movable in slots provided in said piston carrying member, and adopted to move along said channel, and to move also in a direction parallel with the axis of the motor; means for moving each of said pistons into 30 said channel after it has moved past said abutment; a rotary guiding member located within said casing and supported by said cam member and adapted to guide said pistons in their movements parallel with said 35 shaft; and a port adjacent said abutment and through which fluid may flow from the interior of said casing into said channel.

In testimony whereof I have signed my name to this specification in the presence 40 of two subscribing witnesses.

MARTIN V. B. ETHRIDGE.
